UNITED STATES PATENT OFFICE.

CHARLES S. EPPLEY, OF YORK, PENNSYLVANIA.

CIRCUIT BREAKER.

Original application filed July 27, 1923, Serial No. 654,223. Divided and this application filed March 10, 1924. Serial No. 698,231.

To all whom it may concern:

Be it known that I, CHARLES S. EPPLEY, a citizen of the United States, residing at York, in the county of York and State of Pennsylvania, have invented certain new and useful Improvements in Circuit Breakers, of which the following is a specification.

This invention relates to improvement in circuit breakers and while the circuit breaker embodying the invention is especially designed for use in connection with the electric control panel for automatic railway switches disclosed in my co-pending application filed July 27th, 1923, Serial No. 654,223, of which this application is a division, the said device may be employed in various other electrical circuits.

One of the objects of the present invention is to provide a circuit breaker which will be positive and instantaneous in its operation to break the circuit in the event of an overload being imposed thereon, so that no damage can result from the imposition of the overload because of any sluggish action of the circuit breaker.

In electrical devices of this class, an arc is very naturally formed at the moment of separation of the contacts which are normally in mutual engagement, and in circuit breakers heretofore designed, so far as I am aware, no means has been provided for disrupting the arc with the result that the contacts are liable to be burned and repairs made necessary. Therefore it is another important object of the present invention to provide means for automatically disrupting and extinguishing the arc substantially at the moment it is formed, or in other words, at the moment the contacts of the circuit breaker are separated.

In the accompanying drawings Figure 1 is a side elevation of a circuit breaker constructed in accordance with the present invention;

Figure 2 is bottom plan view of the circuit breaker;

Figure 3 is a view in end elevation of the circuit breaker.

The circuit breaker embodying the invention comprises an insulating base which is indicated by the numeral 1, and consists of a block of insulating material which is

mounted between two side plates 2, which are of heat-resisting insulating material, and to the outer faces of which are secured 55 plates 3, which support, between their upper ends, an electric magnetic blowout coil indicated by the numeral 4. The plates 3 constitute the pole pieces of the coil 4, and project at their lower portions below the 60 plane of the base 1 has clearly shown in Figures 1 and 3 of the drawings, it being observed that in Figure 1, one of the plates 3 and the insulating piece 2, is omitted in order that other parts of the circuit breaker 65 may be better illustrated. The pole pieces 3 of the electric magnetic coil 4 serve a purpose which will presently be more fully explained.

A wire 5 leads from one end of the winding coil 4 and is connected to one terminal of a resistance element (not shown) which is located in the circuit of the control panel of my said co-pending application. The other terminal of the winding of the said 70 coil 4 leads to a heating coil which is indicated in general by the numeral 6 and which will presently be more specifically described.

At one end the insulating base 1 is cut away or recessed as indicated by the numeral 7, and embedded in the extended portion of the base thus provided, and indicated by the numeral 8, is a spindle 9 having a binding nut 10 on one end to secure the lead 11 from one end of the heating coil 6, the 75 lead from the coil 4 to the other end of the winding of the heating coil being indicated by the numeral 12. Rotatably mounted upon the spindle 9 is a circular disk 13 provided at its periphery at a predetermined point 80 with a notch 14 providing an abrupt shoulder indicated by the numeral 15. A short arm 16 is secured to that end of the spindle opposite the end to which the binding nut 10 is applied, and a spring 17 is 85 coiled about the spindle and secured at one end as at 18 to the disk 13 and at its other end as at 19 at an opening in the arm 16, the spring being so arranged that it has a normal tendency to rotate the disk 90 13 toward the left in Figure 1 of the drawings. The numeral 20 indicates in general a switch blade which comprises a body leaf 100 21 having a right angularly upwardly turned

end 22 secured in the lower side of the periphery of the disk 13 and provided at its outer or free end with a finger button 23. The switch blade 20 likewise comprises a 5 more flexible and resilient leaf 24 which is provided at its free end with a contact button 25 designed to normally engage a contact 26 at the under side of the insulating base 1. A conductor wire 27 is connected to the contact 26 and leads to the 10 motor (not shown) of the control panel circuit of my said co-pending application.

The coil 6 above referred to comprises a winding 28 of wire of a gauge such that it 15 will not heat under normal current conditions, and this winding is arranged about a thermostatic element which is indicated in general by the numeral 29, and which comprises a strip 30 of a metal having a relatively 20 low coefficient of expansion, and a second strip 31 having a considerably higher coefficient of expansion. These strips are both secured at one end upon the insulating base 1 by means of a bolt or other fastening device 32, and the strip 30 is arranged above the strip 31 and has a right angularly downwardly turned end 33 which normally seats within the notch 14 in the periphery of the disk 13 and constitutes an abutment for the 25 shoulder 15. The strips are riveted together and the free end of the strip 31 terminates directly in the angle between the strip 30 and the down turned end 33, and under normal temperature conditions abuts 30 at its extremity against the inner side of the abutment portion 33.

Under normal conditions, the down turned abutment end 33 of the strip 30 of the 35 thermostatic element will constitute an abutment for the shoulder 15, and the disk 13 will be held in the position shown in Figure 1 of the drawings, in which position it will in turn hold the switch blade 21 in a substantially horizontal position and with the contact 25 engaging the contact 26 thereby establishing a circuit through the 40 circuit breaker and the electrical circuit in which it is interposed. Should an overload be imposed upon the circuit, the coil 28 will become heated and will heat the strip comprising the thermostatic element. As 45 the strip 30 has a relatively low coefficient of expansion and the strip 31 has a relatively high coefficient of expansion, the latter strip will expand to a greater degree than the strip 30, and by reason of the engagement of its free end against the inner side of the abutment 33, will, in expanding, deflect or distort the strip 30 sufficiently to 50 cause automatic disengagement of the said abutment 33 from the notch 14 thereupon the spring 17 will immediately act to rotate the disk 13 and thereby bring the switch blade 20 to position with its contact 25 out of engagement with the con-

tact 26, thus breaking the circuit. When 55 normal current conditions have been re-established, the circuit breaker may be readily reset by merely pressing downwardly upon the button 23 and thus imparting rotary motion to the disk 13 until the contact 25 has been again brought into engagement with the contact 26, and the shoulder 15 has passed beneath the abutment 60 33 of the strip 30 and engaged behind the 65 same.

At the moment of separation of the contacts 25 and 26 an arc will of course be formed, but in the meantime the electric magnetic coil 5 has been energized and the 70 magnetic flow from one of the poles 3 to the other pole 3, traversing the path between the said contacts 25 and 26, will deflect the arc laterally and thus disrupt and extinguish the same. The insulating means 2 75 will preferably be of asbestos, although, as heretofore stated, any heat-resisting insulating material may be employed, and as a consequence, they will serve to protect the 80 pole pieces 3 and prevent burning of these 85 elements.

Having thus described the invention, what is claimed as new is:

1. A circuit breaker comprising a base, a fixed contact thereon, a disc rotatably mounted upon the base and having a peripheral shoulder, a spring urging the disc rotatably in the direction in which the shoulder is presented, a thermostatic element comprising mutually united strips, one having a relatively low coefficient of expansion and the other a relatively high coefficient of expansion, the strips being secured at one end to the base, the free end of one strip having an angularly directed abutment engaged by the shoulder upon the disc, the free end of the other strip engaging behind the abutment of the first mentioned strip, a coil surrounding the strips and in circuit with the disc, and a contact comprising a blade secured between its ends to the periphery of the disc and having a contact point at one end engaging the fixed contact, and a finger button upon the other end of the blade. 110

2. A circuit breaker comprising a base, a fixed contact thereon, a spindle fixed upon the base, a disc rotatable upon the spindle and having a peripheral shoulder, a spring 115 upon the spindle fixed at one end with relation thereto and having its other end connected to the disc and urging the disc rotatably in the direction in which its shoulder is presented, a coil in circuit with the disc, a thermostatic element comprising mutually united strips in the field of the coil and one having a relatively low coefficient of expansion and the other a relatively high coefficient of expansion, the strips being secured at one end to the 120

base, the free end of one strip having a downwardly directed abutment engaged by the shoulder upon the disc, the free end of the other strip engaging behind the abutment of the first mentioned strip, and a contact member comprising a strip secured at its intermediate portion to the periphery of the disc and movable bodily with the disc and having a contact point at one end and a finger button at its other end, the contact point of the member being normally in engagement with the fixed contact. ¹⁰

In testimony whereof I affix my signature.

CHARLES S. EPPLER [L. s.]
